[57] ABSTRACT

A device for triggering a signal without the use of mechanical contacts for application in alarm clocks, signal clocks, time switching clocks for electronic devices, start and stop time clocks, short time clocks and the like, consisting of a magnetic dependent electronic control circuit coupled to the clockwork so that a signal is triggered as desired by a changing magnetic field within the clockwork. A plurality of preferably 24 magnetic field dependent resistors are mounted equally from each other on a ring and connected to an inner distribution bar. A second row of magnetic field dependent resistors are connected with an outer distribution bar so that small permanent magnets mounted on a disc and connected with the clockwork of the clock are moved adjacent to the magnetic field dependent resistors at desired preset time intervals so as to operate the electronic control circuit and produce and indication signal.

CONTACTLESS DEVICE FOR ACTUATING A SIGNAL

In the parent German pat. application No. P 18.14 771.2, a device is disclosed which actuates a signal without mechanical contact means in alarm clocks, signal clocks, time switch clocks for electronic devices, start-stop time switches for clocks, start time alarm clocks, and the like. The device consists essentially of a magnet depending electronic control circuit in the clockwork. To trigger a signal, a change in the magnetic field is obtained by the triggering means for the circuit. In accordance with a preferred embodiment of the invention in the parent application a constant magnet is mounted on the triggering lever. After actuating the lever by the clock, the constant magnet is brought to a position which is adjacent to the resistor which depends from the magnetic field.

The present invention improves the devices discussed in the parent application by providing a device for triggering a signal without mechanical contact means. The device can be preset level of the control circuit. The circuit includes a plurality of preferably 24, or 12 first rows of magnetic field dependent resistors equally separated with respect to each other on a circular holder, such as for example an annulus. These resistors are connected to an inner conductive distribution bar, and also with a second row of magnetic field dependent resistors. The second magnetic field dependent row of resistors are connected with an outer distribution bar and are so arranged that small permanent magnets can be mounted thereon. A disc runs above the distribution and is connected, by means of an axis, with the clockwork of the clock. A small permanent magnet is mounted on the disc and can be moved about the first magnetic field dependent resistors at the desired preset intervals. The inventive means allows a signal to be triggered at desired intervals without the movement of mechanical means. To obtain the selective desired triggering of a signal, a small permanent magnet is mounted in a corresponding magnetic field dependent resistor on the second row of the magnetic field dependent resistors. When the small permanent magnet, which is mounted on the disc, is above a corresponding first magnetic field dependent resistor on the annulus, both resistors are subjected to changes in the magnetic fields, so that the subsequent electronic control circuit triggers the signal.

It is therefore an object according to the present invention to provide a device for triggering a signal without mechanical contact means for use in alarm clocks, signal clocks, time switching devices for electronic circuits and the like.

It is another object according to the present invention to provide a contactless switching device which utilizes magnetic field dependent resistors and permanent magnets.

It is still a further object according to the present invention to provide a contactless switching device which is simple in design, easy to manufacture and reliable in operation.

Other objects and features of the present invention will become apparent from the following detailed description considered in connection with the accompanying drawings which disclose the embodiments of the invention. It is to be understood however, that the drawings are designed for the purpose of illustration

only and not as a definition of the limits of the invention.

In the drawings wherein similar reference characters denote similar elements throughout the several views:

5 FIG. 1 is a schematic drawing of the inventive device; FIG. 2 shows one embodiment of the inventive switching arrangement with respect to FIG. 1; and

10 FIG. 3 shows a further embodiment of the inventive switching arrangement in accordance with FIG. 1.

15 Referring to FIG. 1, 24 magnetic field dependent resistors 2 are mounted equally from each other on a ring 1. Magnetic field dependent resistors 2 are arranged so that they correspond to 1 rotation per hour, i.e., 24 hours per day. The magnetic field dependent resistors

15 2 are connected with an inner conductive distribution bar 3. Distribution bar 3 is connected to a connection point 5 by means of a feed line 4. The opposite end of each magnetic field dependent resistor is connected to a further magnetic field dependent resistor 6. Magnetic

20 field dependent resistors 6 are connected vertically with respect to each other in two rows at the right and left sides of ring 1. The opposite ends of the resistors are connected to an outer distribution bar 7. Distribution bar 7 is connected to a contact point 8. The two

25 rows of the resistors 6, which are preferably arranged as shown in the drawing, may be provided with cylindrical permanent magnets 9 which are movable in longitudinal direction as indicated by dotted lines at 9'. In this arrangement, a preselected interval can be chosen to

30 trigger the signal.

35 The signal is triggered by a disc 10 which is mounted on an axis 11 which in turn is connected with the clockwork. A small permanent magnet 12 is mounted on the disc. The disc turns in the direction of arrow 13 within each hour between the individually arranged resistors 2 on the distribution bar on ring 1. Disc 10 is located centrally with respect to the clockwork within ring 1, so that permanent magnet 12 moves each hour from one resistor 2 to the next.

40 45 When permanent magnet 12 moves to a resistor 2 which is connected with another resistor 6 when permanent magnet 9 is at 9', both resistors are switched in series and are subjected to a magnetic field. The resistance value changes so that the subsequent switching arrangement triggers the signal. This signal can switch on devices as long as magnet 12 is positioned above the corresponding magnetic field dependent resistor 2. If it is required to have a signal triggered every hour, permanent magnets 9 have to be mounted on each one of the magnetic field dependent resistors 6, so that the permanent magnet jumps to the next magnetic field dependent resistor 2 after each hour, thus triggering a signal. Alternate switching on and off can also be obtained in each hour if desired.

50 55 In FIG. 2, a further switching arrangement is shown for triggering a signal in accordance with the device discussed with respect to FIG. 1. The terminal 5 of the two input terminals 5 and 8 of two distribution bars 3 and 7 connects to a resistor R and to a Gate G of a Triac T. Terminal 5 is also connected to a variable resistor, which is P connected to one output of Triac T. The other end of resistor P is connected to a capacitor C, which is connected with the second terminal 8. Terminal 8 is further connected with the second output of Triac T, and with one terminal of an alternating current source of 200 volts through fuse S. The alternating current power source is bridged by a generator capaci-

60 65

tor C_2 . The second terminal of C_2 is connected to one output of Triac T through a load resistor L, and choke coil Dr. Load resistor L can be any suitable electric or electronic switchable device. The switch operates as follows:

When permanent magnet 12 of disc 10 (FIG. 1) is positioned above a magnetic field dependent resistor 2 which is connected with a magnetic field dependent resistor 6 on which a permanent magnet 9 is mounted, the total resistance value fed to terminals 5 and 8 is changed. The voltage at gate G thus moves into the range of the ignition voltage for the Triac. The Triac is then switched on, and the alternating current is connected across load resistor L. The capacitor C_2 and choke coil Dr. prevent low frequency and high frequency interference pulses from entering the system.

FIG. 3 shows a further embodiment of the novel switching arrangement for triggering a signal with the device shown in FIG. 1. A zero voltage trigger CA 3059 (an RCA electronic Component) is connected on the two connecting points 5 and 8. A further terminal of the zero voltage trigger is connected to one output of the Triac through resistor R_1 , while another terminal is connected to the other output of the Triac and one pole of the alternating current source by means of a fuse Si. The output terminal of the zero voltage trigger is connected to Gate G of Triac T. A load resistor L is arranged in the same manner as described with respect to FIG. 2.

The use of a zero voltage trigger is advantageous in that the filtering combination consisting of choke Dr. and capacitor C_2 is not needed. The zero voltage trigger always switches on and off while passing through the zero of the sine voltage, so that no low or high frequency interference signals exist.

It is also possible to compliment the device of FIG. 1 by a second system. In this system, a further ring 1 cooperates with a further disc 10 which is provided with a permanent magnet and connected with the minute cycle of the clockwork. With this arrangement, the inner and outer distribution bars 3 and 7 may be switched in series with respect to each other. It is then possible to trigger a signal every $2 \frac{1}{2}$ minutes or every 5 minutes, respectively. A signal will be triggered when all four magnetic depending resistors, which are switched in series with respect to each other, are subjected to the magnetic fields of magnets 9 and 12.

Where plurality of resistors 2 and 6 are switched in series with respect to each other, and are switched parallel due to the two distribution bars 3 and 7, only a very low total resistance exists. Such a low total resistance makes a bridge control rather difficult. Therefore, it is suggested, in accordance with the invention, that the inner distribution bar 3 not be used. Instead it is recommended that the ends of resistors 2, which are mounted on the ring, be connected with an Inverter Gate switch.

In the embodiment of FIG. 4, which uses an Inverter-Gate Switch, inner magnetic dependent resistors 2 are connected to the positive pole of a direct current source of about 5 volts through resistors R_{x1} , R_{x2} – R_{x12} . The common connection points between magnetic dependent resistors 2 and resistors R_{x1} are connected to two sextuple inverters SN 7404 N. This connection is always at the input of the inverters. The outputs of the sextuple inverters are connected to a NAND Gate SN 7430N which have eight inputs and one output. The in-

verters and the NAND gate are integrated circuits. The output of the NAND Gates SN 7430N are coupled together to form output terminal Y at which the TTL level exists.

As can be seen from FIG. 5, the input E of zero voltage trigger N is connected with terminal Y of the inverter Gate arrangement of FIG. 4. The output of the zero voltage trigger is connected with Gate G of Triac T. Load resistor L is mounted in the circuit of Triac T. The switching arrangement of Figs. 4 and 5 operate as follows:

As mentioned in the discussion of the circuit of FIG. 1, one or a plurality of permanent magnets are mounted onto one or a plurality of magnetic dependent resistors 6, according to the time at which a signal should be triggered. When magnet 12, which is mounted on rotating disc 10 approaches magnetic dependent resistor 2 which is switched in series with resistor 6 with permanent magnet 9, the switching threshold of inverter SN 7404N is exceeded and a signal is fed to NAND Gate SN 7430N. At output Y of the NAND Gate, a TT1 signal of about 5 volts is created. This signal is guided to the input E of zero voltage trigger N, and can be used for actuating the zero voltage trigger. The output of the zero voltage trigger N is connected with gate G of Triac T. Load resistor L is mounted in the circuit of Triac T. The two sextuplet inverters SN 7404N and the two NAND Gates SN 7430N are connected to the direct current source of about 5 volts.

Instead of zero voltage trigger N having a subsequent Triac T, any suitable electronic or conventional relay may be used. It was also found that the switching threshold falls in a temperature range of between 40° C to plus 70° C, even with a high degree of dampness in the air. Therefore, the inventive device is particularly suitable in regions with severe changes in the weather condition with a high degree of variations in the temperature where the use of mechanical switching means cannot be used.

While only a few embodiments of the present invention have been shown and described, it is obvious that many changes and variations may take place without changing the character and scope of the invention.

I claim

1. A contactless device for triggering a signal, comprising:
  - a plurality of first, spaced-apart magnetic field dependent resistors, disposed in an annular arrangement;
  - an electrically conductive, inner distribution bar coupled to each of said first magnetic field dependent resistors;
  - a plurality of second, spaced-apart magnetic field dependent resistors, each coupled in series with a corresponding one of said first magnetic field dependent resistors;
  - an electrically conductive, outer distribution bar, coupled to each of said second magnetic field dependent resistors;
  - a rotatable disc, disposed adjacent said annular arrangement of said first magnetic field dependent resistors, and movable about the center of said annular arrangement at a predetermined speed;
  - at least one first permanent magnet, mounted on said disc adjacent said annular arrangement of said first magnetic field dependent resistors; and

at least one movable second permanent magnet, disposed adjacent said second magnetic field dependent resistors,

whereby said distribution bars are electrically coupled by selected ones of said first and second magnetic field dependent resistors adjacent which said first and second permanent magnets are disposed.

2. The device as recited in claim 1, further comprising a triac switch circuit, having its input and gate terminals coupled to said inner and outer distribution bars, and a power source and a load resistor, coupled to the input and output terminals of said triac circuit, so that said triac circuit is activated and couples said power source to said load resistor when selected ones of said first and second magnetic field dependent resistors are coupled by said first and second permanent magnets.

3. The device as recited in claim 1, further comprising a zero-voltage trigger circuit, having its input coupled to said inner and outer distribution bars, a triac having its gate terminal coupled to the output of said zero-voltage trigger circuit, and its input terminal coupled to said zero-voltage trigger circuit, and a power source and a load resistor coupled to the input and output terminals of said triac, so that when selected ones of said first and second magnetic field dependent resistors are coupled by said first and second permanent magnets said triac is triggered and said power source is coupled to said load resistor.

4. The device as recited in claim 2, further comprising fuse means, coupled in series between one terminal of said power source and the output terminal of said triac circuit.

5. The device as recited in claim 4, wherein said fuse means comprises a magnetic fuse.

6. The device as recited in claim 1, further comprising a direct current source, and wherein said inner distribution bar comprises an integrated inverter, coupled to said second magnetic field dependent resistors, having its input terminal connected to said direct current source, and further comprising a plurality of NAND gates coupled to an output terminal of said inverter.

7. The device as recited in claim 3, further comprising a direct current source, and wherein said inner distribution bar comprises an integrated inverter, coupled to said second magnetic field dependent resistors and having its input terminal coupled to said direct current source, and further comprising a plurality of NAND gates coupled to an output terminal of said inverter.

8. The device as recited in claim 2, further comprising a direct current source, and wherein said inner distribution bar comprises an integrated inverter coupled to said second magnetic field dependent resistors, having its input terminal connected to said direct current source, and further comprising a plurality of NAND gates coupled to an output terminal of said inverter.
